UNITED STATES PATENT OFFICE.

LEONARD S. BEALS, OF ASTORIA, NEW YORK.

DESIGN FOR BRACELET.

Specification forming part of Design No. **7,929**, dated December 15, 1874; application filed November 28, 1874.
[Term of Patent 3½ years.]

To all whom it may concern:

Be it known that I, LEONARD S. BEALS, of Astoria, in the county of Queens and State of New York, have invented a Design for Bracelet, of which the following is a specification:

The nature of my design is fully represented in the accompanying drawing, to which reference is made, and in which drawing—

Figure 1 represents a face view. Fig. 2 is a rear view.

Similar letters indicate corresponding parts.

The face of my bracelet is formed in imitation of the twig A of a rosebush, composed of a series of leaves, *a*, between which are placed two roses, *b*, and a flower-bud, *c*, of the species *nasturtium*. A leaf, *d*, of another kind is added to the leaves *a*. The wristband B is com-

posed of a series of beads, which are composed of two outside rolls, and an intermediate short roll.

What I claim as new, and desire to secure by Letters Patent, is—

1. The design for the face of a bracelet, as shown and described.
2. The design for the face and wristband of a bracelet, as shown and described.

In testimony that I claim the foregoing I have hereunto set my hand and seal this 24th day of November, 1874.

LEONARD S. BEALS. [L. S.]
